UNITED STATES PATENT OFFICE.

JAMES H. BURKE, OF ROSSMOYNE, OHIO.

GATE.

1,330,843.

Specification of Letters Patent.

Patented Feb. 17, 1920.

Application filed August 22, 1919. Serial No. 319,144.

To all whom it may concern:

Be it known that I, JAMES H. BURKE, a citizen of the United States, residing at Rossmoyne, in the county of Hamilton and State of Ohio, have invented certain new and useful Improvements in Gates, of which the following is a specification, reference being had to the accompanying drawings.

This invention relates to an improved gate, which may be particularly adapted for use as an elevator shaft gate or adapted as a farm or garden gate.

One of the objects of the invention is to provide a gate of this kind comprising a pair of gate sections, which may be open by collapsing them upwardly and laterally toward and adjacent the opposite gate posts, to permit of a passage through the gate opening.

20 A further object of the invention is the provision of means for assisting materially in opening the gate sections, when first having been started on their opening operations.

A further object of the invention is the provision of means for starting the gate sections on their opening operations.

30 A further object of the invention is the provision of means for holding the gate sections closed, which means comprises a toggle link brace connecting between parts of one of the gate sections, to hold one gate section closed or down, and which gate section includes additional means to overlie a part of the other gate section, whereby it is held down in a closed position.

The invention further aims to provide a gate of this character which is simple, efficient and practical in construction and may be manufactured for a relatively low cost 40 and sold at a reasonable profit.

The invention further aims to provide a gate section comprising a plurality of vertically arranged collapsible slats, supporting members therefor, to which the slats are pivotally connected, whereby the slats may collapse toward and in contact with the posts when the gate section is raised, thereby opening the gate section, so that the parts may assume compact positions relative to 50 each other.

A further object of the invention is to provide a gate of this kind which is especially adapted for use in connection with elevator shafts, in lieu of sliding gates, and a further 55 object of the invention is the provision of

means carried on the gate sections, to prevent persons from leaning over the gate and looking up or down the elevator shaft.

While the design and construction at present set forth and illustrated is deemed preferable, it is obvious that as a result of a reduction of the invention to a more practical form for commercial purposes, the invention may be susceptible to changes, and the right to these changes is claimed, provided they are comprehended within the scope of what is claimed.

The invention comprises further features and combination of parts, as will be herein-after set forth, shown in the drawings and 70 claimed.

In the drawings,

Figure 1 is a view in perspective, showing the improved gate constructed in accordance with the invention, showing the gate closed. 75

Fig. 2 is a vertical sectional view through the gate posts, one of which is hollow or in the form of a boxing, the other constituting an upright, and illustrating the gate sections in elevation and in open positions, illustrating the means for raising or opening the gate sections.

Fig. 3 is a horizontal sectional view on line 3—3 of Fig. 1, at a point immediately above the gate sections, thereby more clearly 85 showing the detail construction.

Fig. 4 is a view showing one of the gate sections in elevation and its posts in section to show the electrical means for operating the gate sections and showing a part of the 90 other section, so as to illustrate how it is held down by the holding means of one of the gate sections.

Fig. 5 is a view in elevation of one of the posts showing one of the gate sections collapsed thereagainst. 95

Referring more especially to the drawings, 1 and 2 designate the gate posts, and the post 1 is in the form of a single upright as shown, and has journaled in forks in its 100 upper end a pulley 3. Secured to the side of the upright or post 1 is a cushioning member 4, which may be constructed of rubber, though not necessarily, for any other suitable material may be used, so as to cushion the gate section when it is raised. The upright or post 1 at a point substantially midway its upper and lower ends is provided with an opening 5, in which a casting 6 is fixed or secured, as shown at 7. A pul- 110

ley 8 is journaled in bearings of the casting 6, and is in alinement with the pulley 3. The pulley 3 is also carried in a casting, as indicated at 9. The post 2 comprises an upright 10, to one face of which a suitable boxing or housing 11 is secured, in any suitable manner (not shown). Secured at 12 to the upright 10 is a casting 13, in which a pulley 14 is journaled. The upper end of the housing or boxing 11 is closed as shown, and carried by one face of the upright 10 is a cushioning member 15, similar to the cushioning member 4, and may be constructed of similar material, and is designed for the same purpose. The upright 10 at a point substantially midway the upper and lower ends of the upright is provided with an opening 16, to receive the casting 17, in which a pulley 18 is journaled. The pulley 18 is in alinement with the pulley 14.

The gate comprises a pair of gate sections 19 and 20, and each gate section comprises the upper and lower bars 21 and 22, which are zigzag in form, though not necessarily, for it is obvious that any other form of construction may be utilized. However, these upper and lower bars are constructed zigzag, so as to provide horizontal parallel portions 23, to which the vertical slats 24 are pivotally connected, since the upper and lower bars are inclined in horizontal planes. In this manner the vertical slats 24 are held in stepped relations, relatively to each other.

Secured to the adjacent faces of the gate posts are upper and lower plates 25 and 26, to the lateral ears 27 of which the upper and lower gate bars 21 and 22 are pivotally connected. One of the slats of each gate section is secured in place by the pivot pins or bolts 28 on which the upper and lower bars 21 and 22 are mounted. Pivotally mounted upon the ears 29 of the plates 25, as at 30 are the back braces 31, which have their other ends connected pivotally to the upper and lower bars 21 and 22 as at 32. The upper and lower braces 31 act to reinforce the gate section, in such manner as to render the same rigid, particularly when closed, thereby preventing the gate section from being forced or wrenched in one direction or the other laterally.

When opening the gate sections, the upper and lower bars 21 and 22 and 31 collapse against the gate posts, while the slats 24 engage the gate posts edgewise, and in parallelism, so that the gate sections may assume compact positions.

Pivoted to the gate post 10 is a toggle link 33, and pivoted at 34 to one of the lower bars 31 is a second toggle link 35, which in turn is pivotally connected as at 36 to the toggle link 33. The adjacent ends of the toggle links 33 and 35 are so united as to permit them to move pivotally relatively to each other in one direction only,

that is in an upward direction and when moved in a downward direction, the toggle links are limited in alinement with each other, and are disposed in an inclined position as shown. To accomplish this one of the toggle links is provided with an abutment extension 37, which underlies one of the lower bars 31, thereby limiting the gate section in its downward closed position, and at the same time locking the gate section, so as to prevent the same from being manipulated upwardly to an open position. However, as soon as the joint between the two toggle links is caused to move upwardly and inwardly, the toggle links will automatically collapse, and the gate section will automatically open, as will be hereinafter described. The gate section 19 has secured thereto as at 38 a bar 39, which overlies the lower bar 22 of the gate section 20 when lowered. It will be seen that when the gate section 20 is lowered, and also the gate section 19, the toggle links will hold the gate section 19 lowered, while the bar 39 overlying the gate section 20 will hold the gate section 20 lowered, thereby in this manner closing the entire gate.

A cable 40 is attached to the gate section 19 as at 41 and passes over the pulley 13, then over the pulley 14 and has its other end provided with a weight 42. A second cable 43 is attached at 44 to the gate section 20, passing over the pulley 8, up over the pulley 3, then toward the fence post 2, and thence over the pulley 14, and is spliced as at 45 to the cable 40. When the toggle links are collapsed, so that their pivotal connection will move upwardly and inwardly, the weight 42 will then act upon the cables and raise the gate sections, so that they will collapse toward and in contact with the posts. When the gate sections are moved pivotally to their open positions, they will be cushioned by the cushioning members 4 and 15, which are carried by the posts 1 and 2.

Coil springs 46 are mounted upon the posts 1 and 2 and these springs are conical, and are designed to be engaged by certain of the slats 24, and when the gate sections are collapsed, thereby compressing the springs. When it is desired to lower the gate sections, in fact, close them, the springs 46 will act to stop them on their downward movements.

If desired, the cables may be actuated by electrical means, and in this case, a suitable solenoid 47 is mounted in the boxing or casing 11, including a core, 48 to which the cable 40 is connected. The solenoid has the usual windings, which are on the usual spool. This solenoid 47 is connected to a battery 47^a by means of the leads or wires 47^b and 47^c or to any other suitable supply of electrical energy, there being a push but-

ton or other switch 51 connected in the lead 47^b for closing or opening the circuit. When the circuit is closed the solenoid is energized, thereby drawing the core thereinto, thereby creating a pulling action on the cables 40 and 43, thereby collapsing the gate sections. However, before actuating the push button 51, the links 33 and 35 are collapsed outwardly.

- 10 The gate sections are provided with additional brace bars 53, which are so disposed, as to prevent persons from leaning over the gate, and looking up or down the elevator shaft, when the gate is employed for use 15 in connection with elevator shafts. This brace 53 is reinforced by the brace 54, which extends downwardly from the brace 53 to the lower part of the gate, and is secured as at 55 to the gate section. It is an object 20 of this invention to employ the gate for use in connection with elevator shafts and when so used, it is the aim to electrically operate the gate sections.

The lower portions of the adjacent ends 25 of the gate sections are provided with cushioning members 31^a to cushion the gate sections when lowered.

The invention having been set forth, what is claimed as new and useful is:

- 30 1. In a gate, the combination with gate posts, of a pair of collapsible gate sections pivotally mounted upon said gate posts, and adapted when collapsed, to lie against the adjacent faces of the posts, means carried 35 by one of the gate sections to hold it closed or extended downward, and means carried by one of the gate sections to overlie the other gate section, to hold the two sections closed.
- 40 2. In a gate of the kind set forth, the combination with a pair of gate posts, of a pair of collapsible gate sections pivotally mounted upon the adjacent faces of the posts, and adapted when collapsed, to lie 45 flat against the adjacent faces of the posts, toggle link connections between the parts of one of the gate sections and the stationary part of the gate section to hold the gate section in its downward or extended position, and a device carried by one of the gate sections to overlie the other gate section, to

hold the two sections extended downward in closed positions.

3. In a gate as set forth, the combination with a pair of gate posts, of a pair of collapsible gate sections pivotally mounted upon the adjacent faces of the posts, and adapted, when collapsed, to lie against the adjacent faces of the posts, and means mounted on one of the posts and having connections with said gate sections for opening the gate sections in collapsed positions in contact with the adjacent faces of the posts.

4. In a gate, the combination with a pair of gate posts, of a pair of collapsible gate sections pivotally mounted upon the adjacent faces of the posts, adapted when collapsed, to lie against the adjacent faces of the posts, means for locking the gate sections in extended downward closed positions, means automatically collapsing the gate sections when the locking means is released, and means coöperating with parts of the gate sections to start them on their downward movement, said means for raising the gate sections comprising a solenoid including a core, and connections between the core and the gate sections for raising the same, when the solenoid is energized, and an electric circuit including the solenoid 80 and the core, whereby when it is closed, the solenoid is energized and the core is drawn thereinto.

5. In a gate, a gate post, of a collapsible gate section pivotally mounted upon the gate 85 post, said gate section comprising upper and lower bars having zigzag parts pivotally connected to the post, brace bars for the first bars and having their outer ends connected to the first bars and their inner ends 90 pivoted to the post, the pivots of both sets of bars respectively being axially alined, whereby as the gate section is tilted upwardly the bars will lie flat against the post, and vertical slats connecting the upper 95 and lower zigzag bars and adapted to lie flat against the posts when the sections collapse.

In testimony whereof I hereunto affix my signature.

JAMES H. BURKE.
